(57) **CLAIM**

The ornamental design for a payment device frame, as shown and described.

DESCRIPTION

FIG. 1 is an isometric view of a payment device frame, illustrating an embodiment;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is an exploded view of the payment device frame of FIG. 1.

The broken lines in the drawings depict a payment device received by the payment device frame and form no part of the claimed design.
